(57) **CLAIM**

The ornamental design for a hair clipper unit assembly, as shown and described.

DESCRIPTION

FIG. 1 is a perspective view of the clipper body of a hair clipper unit assembly, where the clipper body is in a first configuration of use;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2;

FIG. 10 is an enlarged view of portion 10 shown in FIG. 7;

FIG. 11 is a perspective view of a first embodiment of the comb of the hair clipper unit assembly;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is a perspective view of a second embodiment of the comb of the hair clipper unit assembly;

FIG. 20 is another perspective view thereof;

FIG. 21 is a front elevational view thereof;

FIG. 22 is a rear elevational view thereof;

FIG. 23 is a left side elevational view thereof;

FIG. 24 is a right side elevational view thereof;

FIG. 25 is a top plan view thereof;

FIG. 26 is a bottom plan view thereof;

FIG. 27 is a perspective view of a third embodiment of the comb of the hair clipper unit assembly;

FIG. 28 is another perspective view thereof;

FIG. 29 is a front elevational view thereof;

FIG. 30 is a rear elevational view thereof;

FIG. 31 is a left side elevational view thereof;

FIG. 32 is a right side elevational view thereof;

FIG. 33 is a top plan view thereof;

FIG. 34 is a bottom plan view thereof;

FIG. 35 is a perspective view of a fourth embodiment of the comb of the hair clipper unit assembly;

FIG. 36 is another perspective view thereof;

FIG. 37 is a front elevational view thereof;

FIG. 38 is a rear elevational view thereof;

FIG. 39 is a left side elevational view thereof;

FIG. 40 is a right side elevational view thereof;

(Continued)

FIG. 41 is a top plan view thereof;
FIG. 42 is a bottom plan view thereof;
FIG. 43 is a perspective view of the hair clipper unit assembly, shown in use with the clipper body working with the first embodiment of the comb;
FIG. 44 is a perspective view of the hair clipper unit assembly, shown in use with the clipper body working with the second embodiment of the comb;
FIG. 45 is a perspective view of the hair clipper unit assembly, shown in use with the clipper body working with the third embodiment of the comb;
FIG. 46 is a perspective view of the hair clipper unit assembly, shown in use with the clipper body working with the fourth embodiment of the comb;
FIG. 47 is a perspective view of the clipper body of the hair clipper unit assembly where the clipper body is in a second configuration of use;
FIG. 48 is a perspective view of the clipper body of the hair clipper unit assembly where the clipper body is in a third configuration of use;
FIG. 49 is a perspective view of the clipper body of the hair clipper unit assembly where the clipper body is in a fourth configuration of use; and,
FIG. 50 is an exploded perspective view of FIG. 1.
The evenly spaced broken lines in the drawings depict portions of the hair clipper unit assembly that form no part of the claimed design.

The dash-dot-dash broken lines depict the boundary around the enlarged portions that form no part of the claimed design. The clipper body and combs are shown separately for convenience of illustration.

1 Claim, 50 Drawing Sheets
